ABSTRACT

Exposure control is achieved in a simplified thermographic copy machine by adjusting the spacing of the radiation source with respect to the print roll while maintaining constant speed and constant radiation output.

THERMAL COPYING MACHINE

This invention relates to the thermographic copying of differentially radiation-absorptive graphic originals and in particular to novel copying apparatus used therein.

A form of thermographic copying machine which has achieved widespread popularity is shown in U.S. Pat. No. 2,891,165. In the machine there described, the original and heat-sensitive copy sheet are carried on a transparent belt past a print roll where they are briefly incrementally exposed to intense radiant energy from a line filament lamp supported in a focusing reflector which concentrates the radiation along a narrow line at the surface of the original. Variations in exposure, when required to compensate for changes in ambient temperature, different types and arrangements of sheet materials, or other variables, are achieved by varying the speed of travel of the carrier. Thus the time required to make a given number of copies may vary.

The device of the present invention employs a different and simplified form of control and makes possible the preparation of copies at constant rate. The simplified construction permits significant weight reduction and provides for a readily portable machine.

A presently preferred form of apparatus embodying the principles of the invention in a portable model is illustrated in the accompanying drawing, wherein

FIG. 1 is a view in perspective of the portable thermal copy device in position for transporting;

FIG. 2 is a schematic illustration showing the drive, irradiation, and paper-carrying components of the device largely in cross section, and

FIG. 3 is a schematic illustration of components of FIG. 2 in partially cutaway elevation;

FIG. 4 is a detail view schematically illustrating a form of control linkage; and

FIGS. 5 and 6 show schematically in partial plan and elevational views further details of an optional automatic control assembly.

The copy machine 10 is contained within a case 11 having an extended generally triangularly cross-sectioned handle member 12. An input slot 13 is provided in the top panel 14 along one edge of the handle; an output slot 13 is similarly provided along the opposite edge. An on-off button 15 and a control button 16 occupy positions on the input face of the handle. A louvered ventilation opening 17 is provided on one end as shown; a similar opening, not shown, occupies the opposite end. A receptacle 18 permits connection to be made to an electric plug and cord. The handle 12 is provided with a handhole 19 for convenience in carrying the machine.

Within the case and supported on suitable frame members, not shown, are print roller 21, drive roller 22, belt guide roller 23, idler roller 24, tension roller 25, and motor drive unit 26. The belt guide roller is desirably as described in U.S. Pat. No. 3,149,497. A transparent heat-resistance belt 27 encircles the rollers as shown. A radiation source unit 28 adjacent the print roll provides the required high-intensity radiation. The drive unit is connected to the drive roller through a drive belt 29 and carries a cooling fan 30.

The source unit 28 comprises an elongate coiled tungsten filament lamp 31 supported at one focus of a troughlike elliptically cross-sectioned partial reflector 32. The reflector is supported between end plates 33, 34 which are pivotally supported from the frame, the pivot 35 being indicated for plate 34 in FIG. 4. The opposite end of plate 34 is pivotally supported, by pivot pin 36, from a lever 37 pivotally attached to the frame at pivot 38 and to a bar 39 at pivot 40. The bar 39 terminates in control button 16. Sliding movement of the control button thus pivotally positions the source unit at any desired location, from contact with the belt 27 to some significant distance therefrom. Exact positioning may be estimated from a suitable scale 41 provided for the purpose on the surface of the handle 12.

In use as a copying machine, the device is laid on its side with the input slot 13 upwards and is connected to a suitable source of power. The composite of graphic original and heat-

sensitive copy sheet is fed along the slant surface of the handle 12 into the input slot, while the button 15 is depressed and held, thereby advancing the belt and activating the lamp. The composite enters between the belt 27 and print roller 21 and is carried past the radiation source unit 28 and ejected through the exit slot 13'. The resultant brief exposure to the intense radiation from the lamp 31 causes thermographic reproduction of the original on the copy sheet.

The extent of the heating effect achieved at the image areas, and therefore the accuracy of reproduction, is controlled by the positioning of the control button 16. Maximum utilization of radiation is achieved with the button in full forward position and with the edges of the reflector substantially in contact with the belt. As the reflector is gradually withdrawn from such position, increasing proportions of the radiation are lost from the print zone and the heating effect is lessened. The adjustment makes possible the successful copying of a variety of originals on a variety of copy sheets, at a constant rate.

The pivotal movement of the source unit is sufficient to displace the line of focus of the reflector a significant distance from the surface of the graphic original. Surprisingly, it is found that accurate focusing, to provide the narrowest possible line of intense radiant energy, is not essential to the successful operation of the device. The intensity of the broadened band of radiation is found to be entirely adequate to provide the required increase in temperature at the radiation-absorptive image areas; and the time of irradiation remains sufficiently brief to avoid any significant lateral spread of the heat pattern.

The lamp is operated at fixed power input and hence at fixed radiation output; no current control devices are required. Heat buildup within the machine is held to a minimum, as contrasted with systems wherein movable shutters control the proportion of radiation reaching the print zone by retaining the radiation within the reflector.

Some of the radiation escaping from the source unit through the open spaces adjacent the edges of the reflector may strike the original but at such a low angle as to have substantially no heating effect. Most of the escaping radiation will be directed tangentially of the print roller. While the radiation not reaching the print zone may be absorbed in other machine components, the heating effect is compensated for by the continuous movement of air obtained with the constant-speed fan 30.

The pivot pin 36 operates within an elongate narrow slot in the lever 37 to compensate for the opposing arcs of the lever and the frame 34. In a simplified construction the pin is attached directly to end plate 34 as indicated in FIG. 4, and any adjustment required by change in ambient or machine temperature must then be made through the button 16. In a somewhat more sophisticated device, such control may be made automatic, using a compensating linkage as indicated in FIGS. 5 and 6. In this optional modification, pin 16' extends terminally from a lever arm 51 which is pivotally attached at pivot 52 to a first support rod 53 extending from end plate 33 and at pivot 54 to a second support rod 55 extending from end plate 34. Rods 53 and 55 have a lower coefficient of thermal expansion than does the reflector shell 32, so that as the temperature of the system is increased the pin 16' is moved in a direction tending to cause increased loss of radiation at the print zone. Initial adjustment of the control linkage may be accomplished by altering the positions of the rods 53, 55 through screw adjustments adjacent the supporting plates 33, 34. Spring 56 or equivalent biasing means may be added to overcome any lost motion in the control linkage.

Pressure applied to the button 15 actuates a switch which simultaneously starts the motor unit 26 and turns on the lamp 31. After the copy has been finished and ejected, releasing the button extinguishes the lamp; but the motor continues to run until the device has cooled sufficiently as controlled by a thermostat.

What is claimed is as follows:

1. A thermographic copy machine wherein a composite of graphic original and heat-sensitive copy sheet is incrementally

briefly exposed within a print zone to intense radiant energy from a line source of energy comprising means for operation at constant uniform speed and constant uniform radiation output, and exposure control means for permitting a desired proportion of said radiation output to be directed away from said print zone along the entire said source.

2. The copy machine of claim 1 including a print roller and a transparent heat-resistant belt for incrementally advancing a said composite, and wherein said line source includes a troughlike reflector for directing said radiation toward said print zone, and said control means includes means for positioning said reflector to permit said proportion of radiation to be directed away from said print zone.

3. The copy machine of claim 2 wherein said reflector is mounted for pivotal movement toward or away from said print zone.

4. The copy machine of claim 2 wherein said troughlike reflector has a truncated elliptical cross section and the source of radiation is disposed along a focus thereof.

5. A constant-speed thermographic copy machine comprising a print roller, a transparent heat-resistant carrier contacting said print roller to provide a print zone, means for driving said carrier and print roller so as to advance a composite of graphic original and heat-sensitive copy sheet therebetween and through said print zone, radiation source means including a line source of radiation adjacent said print zone and a reflector for directing the radiation from said source to said print zone, and control means for permitting escape of any desired proportion of said radiation along the entire length of said

radiation source means in a direction away from said print zone.

6. The copy machine of claim 5 wherein said reflector is mounted for pivotal movement toward or away from said control zone and including pivoting means for providing said movement.

7. The copy machine of claim 6 wherein said pivoting means includes internal differential expansion thermostat means for pivoting said reflector away from said control zone as the temperature of said reflector increases.

8. The copy machine of claim 6 wherein said pivoting means includes external handle means and interconnecting linkage means for permitting manual pivotal movement of said reflector.

15 9. The copy machine of claim 7 wherein said reflector serves as one of the differential expansion components of said thermostat.

10 10. The method of operating a thermographic copy machine, having means for incrementally briefly exposing a composite of graphic original and heat-sensitive copy sheet to intense radiation, for effective copying under all appropriate conditions, comprising operating said machine at fixed copying speed and fixed radiation output rate, and adjusting the proportion of said radiation utilized in exposing said composite, to the level required for effective copying, by permitting escape of the remaining proportion in a direction away from the incremental exposure area.

UNITED STATES PATENT OFFICE
CERTIFICATE OF CORRECTION

Patent No. 3,636,350

Dated January 18, 1972

Inventor(s) Harlan L. Krinke

It is certified that error appears in the above-identified patent
and that said Letters Patent are hereby corrected as shown below:

Col. 1, line 41 - "13" should be "13'"

Signed and sealed this 18th day of July 1972.
